UNITED STATES PATENT OFFICE.

HAROLD Y. PRENDERGAST, OF BROOKLYN, NEW YORK.

SOUND BOX FOR TALKING MACHINES.

1,408,776.

Specification of Letters Patent. Patented Mar. 7, 1922.

Continuation of application Serial No. 134,987, filed December 4, 1916. This application filed December 22, 1919, Serial No. 346,750. Renewed July 8, 1921. Serial No. 483,344.

To all whom it may concern:

Be it known that I, HAROLD Y. PRENDERGAST, a citizen of the United States, residing in the city of New York, borough of Brooklyn, county of Queens, and State of New York, have invented a certain new and useful Sound Box for Talking Machines, of which the following is a specification.

This invention relates to improvements in sound boxes, and is a continuation of my abandoned application, Serial Number 134987, filed December 4, 1916.

One of the objects of the invention is the provision of means for concentrating the sound waves emanating from the diaphragm, and conveying such sound waves through a passage so arranged as to preclude diffusion of extemporaneous sound waves in adjacent passages or chambers within the sound box.

20 A further object of the invention is to provide a means for taking the sound vibrations from the central portion of the diaphragm where the clearer and richer tones are reproduced, and subsequently transmit such sound waves through an insulated passage to the tone arm.

Another object of the invention resides in the provision of a resilient enclosed partition or sounding board, so disposed and arranged 30 as to improve the quality of the reproduced sound.

A still further object of the invention is the provision of a sound box provided with means for concentrating the reproduced sound waves at or about the center of the diaphragm, and transmitting same to an outlet opening located eccentrically with reference to the axis of the sound box.

The invention also comprehends improvements in the details of construction and arrangement of parts, which will be herein-after described and particularly pointed out in the claims.

In the accompanying drawings:

45 Fig. 1 is a central section through a sound box embodying the present invention.

Fig. 2 is a section on the line 2—2 of Fig. 1.

50 Fig. 3 is a section on the line 3—3 of Fig. 1, looking in the direction of the diaphragm; and

Fig. 4 is a section on the line 3—3 of Fig. 1, looking in the direction of the tone arm.

55 In the drawings, a sound box is shown as embodying an annular casing 5 open at its

front, but closed at its back by a plate 6, shown secured in place by screws 7, however in lieu of the plate, the structure may be formed integral with the sound box casing. The plate 6 is provided with a tubular boss 60 8 forming a passage for the exit of the sound waves, and to the tubular boss 8 the usual tone arm may be attached.

Extending across the casing 5 and interiorly thereof is a partition 9, which may be formed integral with the casing as shown or separately therefrom when desired, and spaced from the forward face of this partition 9 is a diaphragm 10. The diaphragm 10 is secured at its outer periphery between the 70 rings 11 and 12 preferably of rubber, the ring 11 resting on a shoulder 13 adjacent the margin of the partition 9 and the ring 12 being forced down upon the diaphragm by means of a two part clamping ring 75 composed of annular sections 14 and 15. The section 15 rests upon the ring 12 and the section 14 is exteriorly threaded and cooperates with interior threads in the casing 5, so that when screwed down, it forces the section 15 80 against the ring 12 and clamps the diaphragm in place. Associated with the diaphragm 10 is a stylus bar 16 secured to the diaphragm and mounted on the casing 5 in any suitable manner. 85

As stated, the diaphragm 10 and partition 9 are spaced apart to provide an intermediate sound chamber 17, the outlet of which is an aperture 18 formed in the center of the partition or sounding board 9. 90 It will be noted in this regard that the outlet 18 of the sound chamber is opposite the center of the diaphragm, and since the vibrations of the diaphragm are of the greatest amplitude at its center, the sound waves 95 resulting from the movement of the diaphragm at its center will find exit directly through the aperture 18 into the space intermediate the partition 9 and the back plate 6. 100

It is desired that the sound waves passing from the sound chamber 17 through the outlet 18 be communicated directly to the outlet passage in the boss 8 of the sound box, and in order that such sound waves may 105 not be dissipated or diffused within the space 20^a adjacent the back plate, the outlet 18 of the sound chamber and the outlet of the sound box are connected by a passage which is walled off from said space 20^a of 110

the chamber interiorly of the back plate. This feature is accomplished by positioning one or more elongated rings 19 of resilient material between the back plate 6 and the 5 resilient partition 9, as shown in the drawings. These rings are preferably of rubber but, in any instance, are resilient, yielding or flexible. When disposed, as shown, they form a passage which collects the sound 10 waves at the outlet 18, of the sound chamber 17, and conveys said sound waves directly to the outlet of the sound box with which is associated the tone arm. The object in making the rings 19 of yielding, re- 15 sili ent or flexible character, is to insulate the sound passage without interference with the vibration of the partition 9, if employed as a sounding board and also to preclude rattling or metallic sounds as would be the 20 case if the rings 19 were of hard metallic character. In order to hold the insulating wall or rings 19 in place, a flange 20 may be formed on the plate 6, although this flange may extend from the partition 9, if 25 desired. The side reaches of the insulating wall 19 are preferably spaced apart a distance substantially equal to the diameter of the outlets of the sound chamber and sound box, while said wall is sufficiently extensive 30 to include the remote end of said outlets. It will thus be manifest that the insulating wall 19 forms an insulating passage from the outlet 18 to the outlet in the boss 8 and does not allow the dissipation of sounds in 35 the space 20^a between the back plate 6 and the partition 9. Furthermore, it will be evident that the insulated passage, when associated with the central opening, concentrates the sound waves and insulates same from 40 the extemporaneous sounds in the chamber 20^a.

It is evident that by the construction described, the effective sound waves are collected, and amplified by the resiliency of the 45 partition 9, and are transmitted through a zone which preserves the quality and delivers such waves to the tone arm.

Having thus fully described the invention, what I claim as new and desire to secure by Letters Patent is:—

50 1. A sound box comprising a casing, means extending across the casing and dividing the same into diaphragm and insulating chambers, a diaphragm in the diaphragm chamber, and a constricted passage of insulating material leading from an aperture in the dividing means to an aperture in the wall of the insulating chamber positioned out of alignment with the aperture in the dividing 55 means.

60 2. A talking machine, a tone arm in combination with a sound box divided to form a diaphragm chamber at one side thereof and an insulating chamber at the other side thereof, a diaphragm in the diaphragm

chamber and an insulating passage in the insulating chamber which chamber extends in parallel relation to the diaphragm and has an entrance to the diaphragm chamber centrally thereof, and an outlet to the tone 70 arm adjacent the periphery of the sound box.

3. In a talking machine, a tone arm in combination with a sound box divided by a centrally apertured sounding board to form 75 a diaphragm chamber at one side thereof and an insulating chamber at the other side thereof, said insulating chamber having an outlet communicating with the tone arm eccentrically of the box, a diaphragm in the 80 diaphragm chamber and an insulating passage leading from the central aperture of the sounding board to the outlet to the tone arm.

4. In a talking machine, the combination 85 with a tone arm of a sound box associated with the tone arm off center, said sound box being provided with a diaphragm, a sounding board positioned intermediate the diaphragm and the back of the sound box and 90 provided with a central opening, and a passage leading from the central opening of the sounding board to the off center tone arm and of less area than the chamber intermediate the sounding board and the back 95 of the sound box.

5. A sound box embodying a casing, one side of which is closed by a back plate, a diaphragm and a sounding board peripherally held within the casing in spaced relation to one another and to the back plate to form a sound chamber intermediate the diaphragm and the sounding board, which sounding board is provided with a central sound outlet of appreciably less cross sectional area than the area of the sounding board and the back plate being provided with an off center sound outlet, in combination with an insulating sound duct extending radially of the box and leading directly 100 from the outlet of the sound chamber to the outlet of the sound box.

6. A sound box embodying a casing, a diaphragm and sound board peripherally held therein in spaced relation to one another to 115 provide an intermediate sound chamber, which sound chamber has a central outlet through an aperture in the center of the sounding board and which casing has an off center outlet passing off center through the 120 back thereof, and a resilient, yielding and flexible sound wall duct forming a passage way from the outlet of the sound chamber to the outlet of the sound box to provide an exit for sound from the sound chamber 125 opposite the zone of greatest amplitude of vibration of the diaphragm.

7. A sound box embodying a casing divided to form a diaphragm chamber at one side and an insulating chamber at the other 130

side, a diaphragm in said diaphragm chamber and an insulating passage in and of less area than the second mentioned chamber and communicating with the diaphragm chamber.

8. A sound box embodying a casing divided to form a diaphragm chamber at one side and an insulating chamber at the other side, a diaphragm in said diaphragm chamber and an insulating passage in the second mentioned chamber, the longitudinal axis of which is parallel with the diaphragm, said passage having its entrance centrally of the sound box and its outlet adjacent to the periphery for communicating with a tone arm.

9. A sound box for talking machines, comprising a casing, a diaphragm arranged therein, a partition wall extending across the sound box and having an opening therethrough substantially centrally of the casing, and a restricted passage formed by walls projecting into the space between the partition wall and the rear wall of the casing and leading from said opening toward the peripheral portion of the casing, said passage having its outlet at said peripheral portion.

10. A sound box for talking machines, comprising a casing open at one side and closed at the other, a diaphragm arranged in spaced relation to the closed side, means dividing the box into a diaphragm chamber and an insulating chamber, a narrow walled passage in the last mentioned chamber leading from the central portion of the casing, and insulating means surrounding the walls of the said passage for insulating the sounds from and preventing the diffusion of the vibrations to the walls of the casing.

11. A sound box for talking machines, comprising a casing, a diaphragm arranged therein, a closure for one side of said casing spaced from said diaphragm, a partition intermediate the diaphragm and the closure, a wall between the partition and the closure to form a sound conveying passage, and con-

centrating means surrounding the walls of said passage and in contact with the closure for isolating the sound waves from the diaphragm.

12. A sound box for talking machines, having a sounding board between the diaphragm and sound outlet, and means for confining the sound between said sounding board and outlet to an area substantially less than that of the sounding board.

13. A sound box for talking machines, having a sounding board between the diaphragm and sound outlet, and an insulating sound-confining member arranged between the sounding board and outlet.

14. A sound box for talking machines, having a sounding board between the diaphragm and sound outlet, and an insulating ring-like member including within its outline a portion of the area of the sounding board and the sound outlet.

15. A sound box for talking machines, having a sounding board between the diaphragm and sound outlet, and means for dividing the maximum and minimum vibrations of the diaphragm and delivering such maximum vibrations to the sound outlet.

16. A sound box comprising a casing having a resilient sounding board, a diaphragm resiliently spaced from the sounding board, and an insulating chamber at the opposite side of the sounding board and through which the sound passes to a tone arm.

17. A sound box comprising a casing, having a resilient sounding board, a diaphragm resiliently spaced from the sounding board, and a chamber formed on the opposite side of the sounding board and through which the sound waves from the diaphragm and the sounding board pass to a tone arm, said latter chamber being formed by resilient means interposed between and bearing on the casing and the sounding board.

In testimony whereof, I have signed my name to this specification.

HAROLD Y. PRENDERGAST.
